STUFFED DOLL OR SIMILAR ARTICLE

Amanda V. Snyder, Portland, Oreg.

Application August 30, 1949, Serial No. 4,763

Term of patent 7 years

(Cl. D34—4)

To all whom it may concern:

Be it known that I, Amanda V. Snyder, a citizen of the United States, residing at Portland, in the county of Multnomah and State of Oregon, have invented a new, original, and ornamental Design for a Stuffed Doll or Similar Article, of which the following is a specification, reference being had to the accompanying drawing, forming part thereof, in which:

Fig. 1 is a front view of a stuffed doll, showing my new design.

Fig. 2 is a side view thereof.

I claim:

The ornamental design for a stuffed doll or similar article, substantially as shown.

AMANDA V. SNYDER.
